LOCK

Edward N. Jacobi, Milwaukee, Wis., assignor to
 Briggs & Stratton Corporation, Milwaukee,
 Wis., a corporation of Delaware

Application July 10, 1930, Serial No. 467,031

13 Claims. (Cl. 70—46)

This invention relates to certain new and useful improvements in locks and has as an object to provide a lock structure wherein the movable element or unit which includes the lock cylinder, 5 may be readily removed from the mounting unit by persons authorized to do so.

It is another object of this invention to provide a lock structure of the character described, wherein the movable unit is removable from its 10 mounting unit when in a predetermined position with respect to the mounting unit, and to which it is movable only by the aid of a proper key.

Another object of this invention resides in the provision of depressible means for readily removably securing the movable unit, including the lock cylinder, in its mounting unit, and which may be actuated by a suitable tool to effect removal of the movable unit when in a predetermined relative position with respect to the mounting unit.

20 Another object of this invention resides in the provision of a lock structure of the character described, having a locking bolt which not only serves to releasably secure the movable unit in locked position, but also maintains the movable 25 unit assembled with the mounting unit.

With the above and other objects in view which will appear as the description proceeds, my invention, resides in the novel construction, combination and arrangement of parts substantially 30 as hereinafter described and more particularly defined by the appended claims, it being understood that such changes in the precise embodiment of the herein disclosed invention may be made as come within the scope of the claims.

35 In the accompanying drawing, I have illustrated one complete example of the physical embodiment of my invention constructed according to the best mode I have so far devised for the practical application of the principles thereof, 40 and in which:

Figure 1 is a view partially in section and partially in elevation of a lock structure embodying this invention;

Figure 2 is a cross sectional view taken through 45 Figure 1 on the plane of the line 2—2; and

Figure 3 is a view partially in elevation and partially in section and taken on the plane of the line 3—3 of Figure 1.

Referring now more particularly to the accompanying drawing, in which like numerals designate like parts throughout the several views, the 50 numeral 5 represents a mounting element or unit which for convenience of manufacture comprises an outer casing 6 and an inner shell 7. The casing 6 has its closed end provided with a tubular

projection 8 in which the adjacent end of an armored cable 9 is anchored to provide a conduit through which a motion transmitting element or wire 10 leads from the structure to be locked, not shown, to the lock per se. The inner shell 7 is snugly received in the casing 6 and is secured therein by spinning over the outer peripheral edge 11 of the casing.

Slidably mounted in the bore 12 of the inner shell is a barrel 13 of a movable lock element or unit which comprises the barrel and a lock cylinder 14 mounted therein. The inner closed end 15 of the barrel abuts against a retaining bushing 16 to which the adjacent end of the motion transmitting element 10 is secured as at 17 and which is confined between the inner closed end 15 of the barrel and a washer or follower 18. An expansive spring 19 confined between the washer or follower 18 and the closed end of the casing 6 at all times yieldably urges the entire movable 75 structure which includes the movable lock unit, comprising the barrel 13 and the cylinder 14 and the retaining bushing 16, outwardly of the mounting unit and through the motion transmitting element 10 tends to maintain the structure to be 80 locked, not shown, in its unlocked position.

The longitudinal sliding movement of the movable lock unit is guided by the engagement of a pin 20 carried by the barrel, in a longitudinal slot or guide-way 21 formed in the inner shell 7, 85 and which extends to the outer peripheral edge of the mounting unit to permit withdrawal of the movable unit therefrom.

The longitudinal sliding movement of the movable structure is controlled, and the actuation of 90 the spring 19 restrained, by the engagement of a locking bolt 22 carried by the movable lock unit, in a keeper recess 23 formed in the inner shell 7. As best illustrated in Figure 3, the recess 23 is substantially L shaped and has an elongated longitudinal portion 24 and a transversely off-set portion 25 at its inner end. The portion 25 of the keeper recess is of a width substantially equal to the thickness of the locking bolt 22 and as best illustrated in Figure 2, the bolt 22 is so mounted 100 in the inner end of the barrel as to be yieldably urged to normally engage its outer locking end 26 with the laterally off-set portion 25 of the keeper recess and releasably secure the movable locking unit in its innermost or locked position 105 compressing the spring 19.

To mount the locking bolt 22, the inner portion 110 of the barrel 13 is provided with a transverse opening 27 of a configuration best shown in Figure 2 and having a spring receiving enlargement 28

at one side thereof, the bolt being positioned in the recess 27 with its locking end 26 normally yieldably projected beyond the peripheral surface of the barrel by a spring 29 confined between the bottom 30 of the spring receiving enlargement 28 and a laterally off-set arm 31 on the locking bolt. A pin 32 anchored in the barrel and a projection or tit 33 on the transverse arm 31 serves to maintain the spring in its proper relation.

10 The innermost end of the locking bolt has an elongated opening 34 through which a pin 35, anchored in the inner closed end portion 15 of the barrel, extends, to secure the locking bolt against outward displacement by the spring while permitting the same to be depressed and swung about the pin 35 as a pivot. It is noted that the tendency of the spring 29 is to swing the locking bolt about its retaining pin 35 in a counterclockwise direction, with respect to Figure 2, to align 15 its outer locking end 26 with the transversely off-set extension 25 of the keeper recess, thus automatically engaging the locking bolt with the off-set portion 25 whenever the movable lock unit is moved inwardly into its mounting unit sufficiently far to bring the bolt in alignment therewith.

Disengagement of the locking bolt from the off-set portion 25 to permit movement of the movable lock unit to unlocked position is accomplished by 20 turning the lock cylinder 14. The cylinder 14 is rotatably mounted in the bore 36 of the barrel and is secured against longitudinal movement therein by the engagement of its outer enlarged end 37 with a suitable shoulder formed at the juncture 25 of a counterbore 38 and the bore 36, and by a screw 39 secured in the barrel with its inner end projected into an annular channel or groove 40 formed in the inner end of the lock cylinder.

As is customary, the cylinder 14 is provided 25 with a plurality of locking tumblers 41 which are yieldable urged to engagement with one of a pair of longitudinal grooves 42 formed on the barrel in communication with its bore 36, the tumblers being retractile within the peripheral surface of 45 the cylinder to free the cylinder for rotation upon the insertion of a proper key 43.

At the extreme inner end of the lock cylinder 30 is an eccentrically located driving cam 44 which is adapted to engage the side of the locking bolt opposite its spring 29, and upon rotation of the lock cylinder imparted thereby through the medium of the key 43, rock the locking bolt about its retaining pin 35 against the action of its spring 29 in a clockwise direction with respect to Figure 2, and thus disengage its locking end 26 35 from the transversely off-set portion 25 of the keeper recess.

Upon being disengaged from the transversely off-set portion 25, the locking end 26 of the bolt 30 is aligned with the elongated longitudinal portion 24 of the keeper recess to free the movable lock unit for outward movement by the expansive spring 19. Such outward movement of the movable lock unit is limited by the engagement of the end 26 of the bolt with the outermost end 45 of the elongated longitudinal portion 24 of the keeper recess. The movement of the movable lock unit in the performance of its normal locking functions is thus defined by the length of the 70 longitudinal portion 24 of the keeper recess.

If it is desired to remove the movable lock unit from its mounting unit those authorized to do so may effect such removal by merely inserting a suitable tool 46 into an opening 47 in the 75 outer casing 6, which, being aligned with the

outer end of the locking bolt when the same is in its position engaging the outermost end 45 of the keeper recess, enables the locking bolt to be depressed against the action of its spring 29 until its outermost end is inwardly of the peripheral surface of the barrel, whereupon the action of the spring 19 moves the entire movable unit outwardly as will be readily apparent. With the movable structure thus removed, it is only necessary to remove the screw 39 to permit the lock cylinder 14 to be withdrawn from its barrel 13.

During insertion of the movable unit in its mounting member, it is only necessary to initially depress the locking bolt until it is moved into the bore 12 of the inner shell and to continue the inward movement of the movable unit until the bolt snaps into the off-set portion 25 of the keeper recess.

From the foregoing description taken in connection with the accompanying drawing, it will be readily apparent to those skilled in the art to which an invention of the character described, appertains, that I provide a lock structure having a novel manner of readily removably securing the movable unit in its mounting structure, wherein the locking bolt not only releasably secures the movable unit in locked position and limits its movement in the performance of its normal locking functions, but also provides depressible means for readily removably securing the elements assembled.

What I claim as my invention is:

1. In a lock structure, a mounting unit, a locking unit movable therein in the performance of its normal locking functions, and cooperating abutments carried by the units for removably securing the locking unit in different positions in the mounting unit, one of said abutments being movable by the locking unit to enable the locking unit to move from one position to another, and being movable to inactive position by a tool inserted in one of the units when they are in predetermined relative positions to release the movable unit for withdrawal from the mounting unit.

2. In a lock structure including a mounting unit and a locking unit movable therein in the performance of its normal locking functions, a single member for defining the normal limits of movement of the locking unit, for releasably holding the locking unit against movement at one of said normal limits and for releasably maintaining the units assembled.

3. In a lock structure, a mounting unit, a locking unit movable therein in the performance of its normal locking functions, cooperating means carried by the mounting unit and the locking unit for defining the normal limits of movement of the locking unit in the performance of its locking function, for securing the locking unit at a definite position within its normal range of movement and releasably maintaining the units assembled, one of said means being yieldably maintained in operative position, and means whereby said yieldable means may be moved to inoperative position to disable the cooperating means by a tool inserted into one of the units.

4. In a lock structure including a mounting unit and a locking unit movable therein in the performance of its normal locking functions, a single member for defining the normal limits of movement of the locking unit, for releasably holding the locking unit against movement at a definite position within its normal range of movement and for releasably maintaining the units assembled.

5. In a lock structure, a bored mounting member, a locking unit movable longitudinally therein in the performance of its normal locking functions, a locking bolt carried by the locking unit and normally engaged in a recess in the mounting unit to define the normal limits of movement of the locking unit and to effect its locking functions, disengagement of the locking bolt out of the mounting unit recess releasing the locking unit for withdrawal from the mounting unit, and means whereby the locking bolt may be disengaged from the mounting unit recess. 80
6. In a lock structure, a mounting unit, a locking unit movable longitudinally therein, a locking bolt carried by the locking unit and engageable in an angularly shaped recess, and a single spring to yieldably project the locking bolt into the recess and to cause the same to follow the angular shape of the recess, whereby the locking bolt serves to retain the locking unit in its locked position and also limits its range of movement. 85
7. In a lock structure of the character described, a bored member, a key operable lock cylinder in said bored member, a locking bolt carried by said bored member, said locking bolt having axial and pivotal movement, and a single spring operable on said locking bolt to oppose both axial and pivotal movement in one direction. 90
8. In a lock structure, a tubular casing, a locking unit movable axially in said casing, a locking bolt carried by said locking unit and engageable in a recess formed in the casing, said recess having a longitudinal and a transverse portion and the locking bolt having pivotal and longitudinal movement, a common spring operable on the locking bolt to oppose both pivotal and axial movement thereof and to yieldably maintain the locking bolt in said recess, engagement of the bolt with the transverse portion of the recess securing the locking unit in its locked position against axial movement, a lock cylinder carried by the locking unit to move the locking bolt pivotally out of said transverse portion of the recess and to thereby free the locking unit for axial movement in the casing, said casing having an opening in line with the longitudinal portion of the recess to enable insertion of a tool to depress the locking bolt out of the recess and free the locking unit for withdrawal from the casing. 95
9. In a lock structure, a mounting barrel, a lock cylinder rotatable in the mounting barrel, a locking bolt carried by the mounting barrel and movable transversely of said barrel and pivotally about an axis parallel to the axis of the lock cylinder, a common spring to yieldably urge the locking bolt transversely of the mounting barrel and also pivotally about its pivotal axis, and a cam on the lock cylinder engageable with the bolt to swing the same about its pivotal axis. 100
10. In a lock structure, a board mounting member having an L shaped recess communicating with its bore, one leg of which is substantially axial to the bore and the other substantially transverse thereto, a locking unit slideable axially in the bore of the casing, a locking bolt carried by the locking unit and engageable in said L shaped recess, the engagement of the locking bolt in the transverse portion of the recess securing the locking unit against longitudinal sliding movement and the engagement thereof in the longitudinal portion of the recess permitting defined sliding movement thereof, a single spring to maintain the locking bolt engaged in said recess and to cause the same to follow the shape of the recess and to engage the same in the transverse portion of the recess, and a lock cylinder carried by the locking unit and operable to disengage the locking bolt from said transverse portion of the recess. 105
11. In a lock, a housing, a cylinder movable in said housing, a pivotally mounted bolt carried by said cylinder and adapted to lock the same against movement relatively to said housing, key controlled means for moving said bolt on its pivot to release said cylinder relatively to the housing, a portion of said pivotally movable bolt being operable with said housing at all times to limit the movement of said cylinder relatively thereto. 110
12. In a cylinder lock, a housing, a cylinder movable in said housing, a pivotally mounted bolt for locking said cylinder relatively to said housing, a plug in said cylinder, and means operable by rotation of said plug to move said bolt on its pivot for releasing said cylinder relatively to said housing, and a portion of said pivoted bolt being cooperable with said housing to retain the cylinder against unlimited movement relatively to said housing when said bolt has been key operated to release said cylinder relatively to said housing. 115
13. In a lock, a housing, a cylinder mounted in said housing, a key operated bolt mounted in said cylinder and adapted to cooperate with means on said housing to lock the cylinder against movement relatively to said housing, said bolt being tiltable when key operated to release the cylinder for movement relatively to said housing, and a portion of said bolt being movable into a position to limit the movement of said cylinder relatively to said housing. 120
